[57] CLAIM

The ornamental design for a holder for a shopping trolley, as
shown and described.

DESCRIPTION

FIG. 1 is a top perspective view of a holder for a shopping
trolley showing our new design;

FIG. 2 is a bottom perspective view thereof;

FIG. 3 is a top plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a bottom plan view thereof; and,

FIG. 9 is a top perspective view thereof on a shopping trolley
when in use, the broken lines are for illustrative purposes
only and form no part of the claimed design.
